Fig. 4.

四

A detailed technical line drawing of a mechanical assembly, likely a pump or valve mechanism. The drawing is oriented vertically and features numerous numbered callouts pointing to specific parts. Key components include a central vertical shaft, a top cover plate, and various internal valves and seals. The numbers, which are not in a standard sequence, include 55, 54, 100, 50, 40, 52, 68, 122, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, UNITED STATES PATENT OFFICE.

EDWIN F. BEUGLER, OF BUFFALO, NEW YORK, ASSIGNOR TO E. & B. HOLMES MACHINERY COMPANY, OF BUFFALO, NEW YORK, A CORPORATION OF NEW YORK.

BAND-SAW STAVE-JOINTER.

1,305,053.

Specification of Letters Patent. Patented May 27, 1919.

Application filed February 8, 1917. Serial No. 147,011.

To all whom it may concern:

Be it known that I, EDWIN F. BEUGLER, a citizen of the United States, residing at Buffalo, in the county of Erie and State of New York, have invented new and useful Improvements in Band-Saw Stave-Jointers, of which the following is a specification.

This invention relates to a band saw stave jointer and it has for its objects the provision of improved means for tightening the band saw, preventing it from running off of the supporting wheels about which it runs and also preventing displacement of the same while the stave blank is being operated upon; also to provide improved means for guiding the band saw and giving the same the proper curvature corresponding to the desired bilge which is to be given to the barrel; also to provide improved means for feeding and presenting the stave blanks to the band saw; also to improve the means whereby the stave blanks are gaged preparatory to being cut and held in place during the cutting operation; and to improve the machine in several other details of construction.

In the accompanying drawings:

Figure 1 is a side elevation of the machine embodying my improvements. Fig. 2 is a top plan view of the same. Figs. 3 and 4 are end elevations thereof viewed from opposite ends of the same. Fig. 5 is a fragmentary longitudinal section, on an enlarged scale, taken on line 5—5, Fig. 2. Figs. 6 and 7 are transverse sections taken on the correspondingly numbered lines in Fig. 5. Fig. 8 is a fragmentary top plan view, partly in section and on an enlarged scale, showing more particularly the means for adjusting the track or alinement and tightening the band saw, and the means for gaging and presenting the stave blanks to the saw. Fig. 9 is a vertical transverse section taken on line 9—9, Fig. 8. Fig. 10 is a fragmentary side elevation, on an enlarged scale and partly in section, showing more particularly the means for guiding the saw in curved form at the place where the same operates upon the stave blanks for jointing the same. Fig. 11 is a horizontal section taken on line 11—11, Fig. 10. Figs. 12, 13, 14 and 15 are vertical cross sections taken on the correspondingly numbered lines in Fig. 10. Fig. 16 is a fragmentary horizontal section taken on line 16—16, Fig. 13. Fig. 17 is a frag-

mentary horizontal section of the machine, on an enlarged scale, taken on line 17—17, Fig. 1. Fig. 18 is a fragmentary vertical transverse section taken on line 18—18, Fig. 17. Fig. 19 is a fragmentary longitudinal section, on an enlarged scale, taken on line 19—19, Fig. 17. Fig. 20 is a horizontal section, on an enlarged scale, taken on line 20—20, Fig. 3. Fig. 21 is a plan view of a stave blank showing the manner in which the same is jointed by means of my improved machine.

Similar characters of reference indicate corresponding parts throughout the several views.

The purpose of this machine is to produce convex cuts or joints on opposite longitudinal edges of a stave blank, so that a plurality of staves thus formed will produce a bilge barrel when assembled which tapers from its central enlarged part toward its opposite ends. In Fig. 21 the oblong stave blank is represented by full lines 1 and the convex joints which are produced at opposite longitudinal edges of this blank are represented by the dotted lines 2.

The main frame of the machine in which the several working parts are mounted may be of various forms but as shown in the drawings the same preferably comprises a longitudinal body, beam or girder 3 and two substantially A-shaped standards or pedestals 4, 5 which support the body at its opposite ends and rest upon the floor.

6 represents the endless band saw which has its flat sides arranged vertically and its teeth 7 arranged at the lower edge thereof and which is so mounted as to form two longitudinal operative stretches and two turns which connect corresponding ends of the operative stretches. The turns of this saw pass around two supporting pulleys or wheels 8, 9 which are mounted to revolve about vertical axes. One of these saw supporting pulleys or wheels, for instance the pulley 8 is mounted on the upper end of an upright driving shaft 10 which is journaled in suitable bearings 11 on the adjacent end of the main frame and provided near its lower end with a driving pulley 12 to which power may be transmitted from any suitable source by means of a driving belt. The other band saw pulley or wheel 9 is so mounted that the same may be moved bodily toward and from its companion pulley 8 for

the purpose of tightening the band saw and the same is also capable of being tilted in order to cause the band saw to track properly or run true thereon without liability of creeping on this wheel or throwing the same out of alignment. The means whereby this is accomplished are best shown in Figs. 2, 5, 6, 7 and 8 and are constructed as follows:

13 represents an upright arbor which is arranged above the main frame and on the upper end of which the hub of the band saw wheel 9 is mounted to turn freely. The lower end of this arbor is mounted on a block 14 formed by the hub or outer end of an adjusting arm 15 which latter is capable of longitudinal movement and also a tilting movement. For this purpose this adjusting arm is mounted on a longitudinally and horizontally movable carriage or slide 16 by means of a horizontal pivot pin 17 which passes transversely through the adjusting arm adjacent to the arbor and has its opposite ends arranged in inwardly projecting arms 18 formed on this carriage. The latter is guided at its opposite longitudinal edges in guideways 19, 19 formed horizontally and lengthwise on the upper part of the main frame. The tilting movement of the adjusting arm and the parts mounted thereon is effected by means of an upright adjusting screw 20 arranged in a threaded opening in the inner end of this arm and bearing at its lower end on a horizontal bearing surface 21 formed on the upper side of the adjacent part of the main frame and provided at its upper end with a hand wheel or handle 22 for turning the same. The weight of the adjusting arm and associated parts together with the pull on the band saw against the supporting wheel 9 causes the lower end of the adjusting screw 20 to remain in engagement with the bearing surface 21. By turning this screw in one direction or the other the adjusting arm and the corresponding saw supporting wheel may be tilted as required to cause the same to run true and properly about both supporting wheels. After adjustment the screw 20 may be held in place by any suitable means, for instance by means of a locking pin 23 arranged in a horizontal guide opening in the inner end of the adjusting arm and bearing against this adjusting screw, and a clamping screw 24 arranged in a threaded opening in the adjusting arm and bearing against this clamping pin, as shown in Fig. 5.

The means whereby the adjusting arm and associated parts are adjusted lengthwise of the machine for adapting the supporting pulley 9 to the length of the saw and take up any slack in the same preferably comprise an upright tension adjusting lever which is pivoted by means of a horizontal transverse pin 25 to a pair of lugs 26 pro-

jecting upwardly from the central part of the main frame. This lever is provided with a lower arm 27 which projects downwardly through an opening 28 in the main frame and a bifurcated upper arm each 70 branch or member 29 of which has a circular opening 30 the axis of which is arranged horizontally and transversely relative to the length of the machine. Below the upper part of the main frame is arranged a horizontal pressure bar 31 which is secured at its inner end in an opening in the lower arm of the tension lever by means of a set screw 32 so that this bar in effect forms a part of this lever. To the outer end of this bar is attached the upper end of a weight rod 33 which latter carries at its lower end a weight which is preferably made up of a plurality of sections 34, as shown in Figs. 1, 3, 4 and 5. 85 By varying the number of weight sections and also adjusting the bar 31 relative to the lower arm of the tension lever the effect of the latter for holding the band saw taut may be varied as required. Extending horizontally and transversely through the circular openings in the two upper arm branches of the tension is a fulcrum screw nut or block 35 which is preferably square in cross section and so arranged that it bears 90 with its upper and lower corners as knife edges against the sides of these openings and thereby produces an easy working contact between this fulcrum block and the tension lever. The threaded opening of the fulcrum block or screw nut is arranged between the upper arm branches of the tension lever which opening receives the screw threaded inner end of an adjusting rod 36. The latter is connected at its outer end by a swivel joint with the adjacent inner end of the adjusting arm. This swivel joint may be variously constructed but preferably by a screw nut 37 secured to the outer end of this rod and arranged within a pocket 38 in the inner end of the adjusting arm, as shown in Fig. 5. By means of this adjusting rod the pull of the weights 34 is transmitted from the tension lever to the adjusting arm so that the latter is shifted outwardly lengthwise of the machine and the supporting wheel 9 is caused to bear yieldingly against the respective turn of the band saw, so that no undue slack exists in the same. By turning the adjusting rod 36 the relative position of the tension lever and the adjusting arm may be determined to produce the most effective results; the turning of this rod being preferably effected by means of a hand wheel 39 applied thereto between the fulcrum block and the adjusting arm, as shown in Figs. 2, 5 and 8.

40, 41 represent semi-circular outer guards arranged around the outer sides of the turns of the band saw. The guard 40 associated 130

with the supporting wheel 8 is preferably supported on the main frame by means of a plurality of supporting arms 42 which are arranged substantially radially relatively to this wheel and on the underside thereof and connected at their outer ends with the lower edges of the guard 40 by means of clips 43 while their inner ends are mounted on supporting lugs 44 on the adjacent part of the main frame. The guard 41 associated with the bodily movable supporting wheel 9 is supported by means of a plurality of supporting arms 45, 46 arranged substantially radially below this wheel and secured at their outer ends to the lower edge of the guard 41 by means of clips 47 while their inner ends are mounted in lugs 48 on the horizontally movable carriage 16, as shown in Figs. 5 and 8. The arms 46 supporting the extremities of the guard 41 are preferably formed from a continuous rod which latter passes with its central part through an opening 49 in the adjusting arm, which opening is preferably made sufficiently large, as shown in Fig. 5, to permit the adjusting arm to move vertically the requisite extent as may be necessary for tilting the supporting wheel 9 and causing the band saw to run true.

30 In the organization of this machine, as shown in the drawings, means are provided for presenting stave blanks to each of the longitudinal stretches of the band saw so that two operators can be engaged in this work at the same time, whereby this machine, in effect, is doubled and its capacity increased accordingly. If desired, however, my improvements may be applied to only one stretch of the saw and in the following 40 description of the parts associated with one stretch it is to be understood that the same applies to devices associated with both stretches of the band saw. In the operation of this machine each stave blank is moved horizontally and transversely underneath the saw, then the blank is raised so as to cause its inner longitudinal edge to be trimmed off on a curve by the toothed lower edge of the saw, then the stave blank is lowered and the opposite longitudinal edge thereof is operated upon in like manner for the purpose of completing the jointing of the stave. In order to prevent the saw from being displaced upwardly by the thrust 50 which is exerted against its lower toothed edge upon pressing a stave blank upwardly against the same, guiding devices are provided which coöperate with the band saw adjacent to opposite ends of each of its operative stretches. Each of these guiding devices preferably comprises a guide wheel, roller or disk 50 which is arranged horizontally and rotates about a vertical axis and bears with its flat underside against the upper untoothed edge of the adjacent part of the band saw. This guide wheel or roller is pivotally mounted on the lower part of a bracket 51 which latter is capable of vertical and horizontal adjustment relatively to the saw for the purpose of causing this 70 guide roller to engage properly with the upper edge of the saw. Various means may be provided for effecting this adjustment of the guide roller bracket but as shown in the drawings these means comprise an upright 75 supporting post or rod 52 which is mounted at its lower end on an arm 53 projecting laterally from the body of the main frame. The bracket 51 is capable of moving vertically and also turning horizontally on the 80 upper end of the post. The vertical movement of this bracket is preferably effected by means of an upright adjusting screw 54 working in a threaded opening in the upper end of this bracket and provided at its upper end with a hand wheel 55 while its lower end bears against an abutment 56 arranged on the lower part of the respective supporting post 52. After the horizontal and vertical adjustment of this bracket has 85 been effected for bringing the guide roller 50 into the proper position this bracket is held firmly in place by a clamping device which preferably comprises a clamping rod 57 movable transversely in the upper part of 90 the bracket 51 and having a wedging surface 58 which engages with the periphery of the respective supporting post. The tightening of the clamping rod is effected by means of a screw nut 59 arranged on the threaded end 100 of this rod and engaging with the outer side of the respective bracket 51, as shown in Fig. 20.

Each of the longitudinal stretches of the band saw is deflected inwardly on a curve 105 corresponding to the curve which it is desired to give the longitudinal joint edges of the staves. The means for this purpose which are shown in the drawings as embodying my improvements are constructed as follows:

60 represents a plurality of outer guide bearing blocks preferably of lignum-vita which are arranged in a horizontal row and engage with the outer side of an operative 115 stretch of the band saw at a distance above the toothed lower edge thereof. These bearing blocks are so arranged that they deflect the operative part of the saw inwardly and give the same a curvature corresponding to 120 that desired on the longitudinal edges of the barrel staves. The several outer bearing blocks are mounted on the inner side of a supporting plate 61 preferably of flexible steel by means of rivets 62, as shown in Figs. 125 10, 14 and 15, or by other suitable means. This flexible supporting plate is secured on its outer side at different points in its length to the lower ends of a plurality of outer hangers 63, 73, by means of screws 64, as 130

shown in Fig. 12 or otherwise. The upper ends of these hangers are secured by screws 65 to the upper horizontal flange 66 of a supporting bar of angle or L-shaped cross section. This bar is arranged lengthwise adjacent to the upper edge of the band saw between the companion guide rollers 50, 50 and is mounted on the supporting posts 52 by means of two brackets 67. Each of the latter is provided with a split sleeve 68 which is secured on one of these posts by means of a clamping screw 69 and is also secured to the horizontal flange of this angle supporting bar by means of a lug 70 arranged on this bracket and engaging with the upper side of the angle bar, and a clamping bolt 71 passing through an outwardly opening slot 72 in this lug and an opening in the horizontal flange of the angle bar, as best shown in Figs. 8, 9 and 10. The slots 72 of both brackets 67 permit of adjusting the angle bar bodily transversely of the saw for shifting the outer bearing blocks together relatively to the saw. Each hanger 63 is capable of individual adjustment horizontally and transversely of the angle bar by enlarging the openings 74 in the upper flange of the angle bar which receive the screws 65 whereby the respective outer hanger is connected with the angle bar, as shown in Figs. 12 and 13. By this combined adjustment the flexible supporting plate and the outer bearing blocks mounted thereon may be bent inwardly to form a curved guiding surface for the operative portion of the saw to suit the particular curvature on which the longitudinal joint edges of the barrel staves are to be cut. The location of the outer hangers 63, 73 relatively to the angle supporting bar is preferably determined by means of horizontal push screws 75 arranged in threaded openings in the vertical flange 76 of the angle bar and engaging with the inner sides of the outer hangers, and draw screws 77 engaging with plain openings in the flange 76 and with threaded openings in the hangers 63, 73, as best shown in Figs. 12, 13 and 16. The fine adjustment of the angle supporting bar in a direction transversely of the saw for shifting the several outer bearing blocks together is preferably effected by means of two clamping or adjusting blocks 78 each of which is secured to the rear side of the vertical flange of this angle bar by means of a horizontal transverse bolt 79 and having an upwardly extending part 80 which projects past the inner side of the adjacent supporting bracket 67 and is provided with an adjusting screw 81 extending horizontally and transversely through an opening in the upper extension 80 and bearing against the inner side of the respective supporting bracket 67, as best shown in Figs. 8 and 9.

Each of the operative stretches of the band

saw is held in proper contact with the set of outer bearing blocks by means of two inner retaining blocks 82 preferably of lignum-vite and engaging with the inner side of the band saw at a distance above its lower toothed edge and adjacent to opposite ends 70 of the row of outer bearing blocks. Each of these inner bearing blocks is supported on the lower end of an inner hanger 83 which latter is provided at its upper end with an outwardly projecting horizontal lug 75 84 which rests on top of the horizontal flange of the angle supporting bar and is adjustably secured thereto by means of a vertical bolt 85 passing through the horizontal flange of this angle bar and through a transverse slot 86 formed in the upper lug of the respective inner hanger, as best shown in Figs. 8 and 14.

It has been found in practice that operators are inclined to reach over and downwardly adjacent to the inner side of the toothed edge of the saw for the purpose of removing strips of wood which have been cut from the stave blanks and in doing so they are liable to be injured. To prevent the operator from getting his hands near the inner side of the cutting edge of the saw in this manner a guard 87 is provided which is preferably constructed of wood and arranged lengthwise adjacent to the inner side of the toothed edge of the saw, as best shown in Figs. 10-15. This inner guard is adjustably mounted on the lower ends of two inner guard hangers 88 by means of bolts 89 passing through this guard and vertical slots 90 100 in these hangers. The latter are provided at their upper ends with outwardly projecting lugs 91 which overhang the horizontal flange of the angle bar and are provided with depending guide pins 92 which engage with openings 93 in this flange, as best shown in Fig. 15. On the central parts of the guard hangers 88 the same are provided with forwardly projecting guide lugs 94 engaging with the inner vertical sides of the bar flange 105 76. By this means access of the hands of the operator to the toothed edge of the saw from the inner side thereof is prevented but when a stave blank is raised into engagement with the lower edge of the saw for trimming the same the inner guard would be lifted bodily but if the inner portion of the stave blank projects underneath this guard while being lifted into engagement with the teeth of the saw then this guard will be automatically lifted so as not to interfere with the cutting operation. After the stave blank has been cut and is again lowered the inner guard will descend by gravity into its normal operative position.

In practice a plurality of angle supporting bars together with the necessary inner and outer hangers and bearing blocks and

inner guards are provided each set of fittings being adjusted for cutting barrel staves on some particular curvature. This enables the machine to be changed quicker for cutting 5 different sizes of barrel staves than would be possible by shifting the several inner and outer hangers and their companion bearing blocks to suit some particular curvature of barrel stave which is required. This changing 10 of one set of saw curving devices for another is readily effected by loosening the bolts 79 and withdrawing the same forwardly from the slotted lugs 70 of the brackets 67 and then replacing the same 15 with another angle bar equipped with the desired guiding devices. Inasmuch as the withdrawal of the supporting bar from the slots 72 necessitates shifting the clamping blocks 78 into such a position that their 20 tensions 80 do not project upwardly along the inner sides of these brackets these clamping blocks are turned vertically upon the bolts 79 so that the extensions 80 are arranged below these brackets and they are 25 also turned into this position when the angle bar is re-applied to these brackets. In order to retain the clamping blocks in this abnormal position while the angle supporting bar is moved horizontally out and into its operative 30 position, retaining means are provided which preferably consist of a friction pin or plunger 95 arranged in a horizontal guideway 95a in the lower part of the clamping blocks 78 and held yieldingly in engagement 35 with the rear or inner side of the vertical flange of the angle bar by means of a spring 96 arranged in the bottom of this guideway and the rear end of the plunger, as shown in Fig. 9. When the clamping 40 block is in its normal position the pin or plunger 95 preferably engages with a recess 97 in the angle bar for holding the parts in place more securely. By this means the clamping blocks may be frictionally held in 45 their inoperative position in which their upper parts do not project behind the inner or rear sides of the respective brackets 67 and thereby not interfere with the free application of the angle bar to or the removal 50 of the same from the brackets 67, thereby expediting the changing of the machine for cutting barrel staves on different curves when this is desired.

Although various means may be employed 55 for presenting the stave blanks to be cut or jointed to the band saw those preferred and embodying my improvements are best shown in Figs. 1-4, 8, 17 and 18 and are constructed as follows:

60 Adjacent to the underside of each operative stretch of the band saw is arranged a stave blank carrier which is movable vertically relatively to the same on the outer side of the same. In its preferred form this car-

rier comprises a rest table or support composed of a longitudinal bar 98 and a plurality of forwardly projecting wings or extensions 99. This carrier is mounted at its opposite ends on the outer ends of two vertically swinging rock arms or radius rods 70 65 100 which are arranged transversely underneath the adjacent part of the band saw and are pivotally mounted on the main frame by means of horizontal longitudinal pivot pins 101 passing through hubs 102 arranged on the inner ends of these rock arms and through lugs 103 arranged on the main frame, as best shown in Figs. 2, 8, 17 and 18. The rising and falling movement of these rock arms and the parts mounted thereon 70 75 80 is preferably effected by means of a horizontal rock shaft 104 arranged lengthwise in the lower part of the machine, a treadle 105 secured to the central part of this rock shaft and projecting outwardly therefrom, a longitudinal supporting rod 106 mounted on the lower parts of the frame standards and provided with two bearing hangers 107 in which opposite ends of this rock shaft are journaled and two shifting rock arms 108 90 95 projecting inwardly from said rock shaft adjacent to opposite ends thereof and connected at their inner ends by means of upright connecting rods 109 with blocks 110 on the central parts of the carrier rock arms. 95 Upon depressing the treadle the carrier rock arms 100 and the parts mounted thereon will be raised and upon releasing the treadle these arms and the stave carrier will be lowered by gravity. The downward movement of the stave carrier is limited by stops 117 which are secured to the outer ends of the supporting arms 53 in position to be engaged by the outer parts of the carrier rock arms 100, as shown in Figs. 17 and 18. The 100 weight of this carrier and associated parts is preferably counter-balanced by means of a spring 111 having its upper end connected with an adjacent part of the main frame while its lower end is connected with a lateral extension 112 on one of the inner shifting rock arms 108, as shown in Figs. 1 and 4, thereby easing the work for the operator in the act of raising the carrying table. The central part of the rock shaft 104 is preferably made square in cross section and the hub of the treadle is provided with a corresponding shaped opening which receives this shaft and also with a set screw 113 adapted to clamp this hub on this shaft at different 110 115 points of its length, thereby enabling the operator to readily place this treadle in a position which is most convenient for operating the machine.

The stave blank to be cut or jointed is 125 placed by the operator upon the carrier or rest with one end thereof against a gage 114 which is secured to the top of the table,

preferably at the left hand end thereof, as best shown in Figs. 1, 17 and 18.

- In order to permit of shifting the end gage into different positions lengthwise of the stave carrier to suit different lengths of staves the top of the carrier is provided with a plurality of openings 115 which are arranged in a longitudinal row and one or the other of which receives a screw 16 whereby this end gage is secured to the carrier, as shown in Fig. 17. After the stave blank has been thus placed upon the carrier the same is pushed inwardly or rearwardly thereon, so that its inner or rear longitudinal edge projects across the plane of the adjacent part of the band saw preparatory to raising this blank by means of the carrier and cutting off its inner edge portion. The extent which the stave blank is thus moved forwardly underneath the band saw is determined by a side gage 118 which is preferably arranged opposite the central part of the inner side of the carrier and in the transverse path of the stave blank. In order to enable the side gage to assume this position the inner guard is provided with an opening or notch 119 in the central part of its lower edge through which the side gage projects, as shown in Figs. 10 and 11.
- In order to prevent this gage from interfering with the free upward movement of the stave blank after the latter has been gaged on its inner edge preparatory to being trimmed by the saw this side gage is so mounted that during the initial part of the upward movement of the carrier the same may be withdrawn inwardly away from the inner edge of the stave blank. For this purpose the side gage is mounted on a horizontally swinging rock arm 120 having a hub 121 which is pivoted by means of an upright pin 122 on a bracket 123 mounted on one of the supporting arms 53 preferably the right hand one, a cam 124 arranged on the adjacent carrier rock arm 100 and engaging with a tappet, abutment or roller 125 on the hub of the gage arm and a return spring 126 surrounding the pivot pin 122 and bearing at one end against a collar 127 on this pivot pin while its opposite end bears against the hub of the gage arm, as shown in Fig. 19. When the stave carrier is depressed the spring 126 moves the gage arm outwardly so that the side gage is in its proper position to be engaged by the stave blank while the same is resting on the carrier. The outward movement of the side gage is limited by engagement of the roller 125 with the low part of the cam 124, as shown in Figs. 17 and 18. During the first part of the upward movement of the stave carrier the cam 124 by engaging with the roller 125 causes the gage arm and the side

gage to be swung inwardly away from the stave blank and thereby avoid displacing the latter after it has been gaged preparatory to being operated upon by the band saw.

Means are provided which permit of moving the stave blanks inwardly on the stave carrier so that its longitudinal edges are arranged even and in the proper position relative to the saw for trimming off the longitudinal edges of the stave uniformly. This movement of the stave blanks is preferably effected by two evener or placing jaws 128 which are arranged adjacent to the outer side of the carrier and mounted on the upper ends of two transversely swinging evener rock arms 129 which are secured at their lower ends to a horizontal rock shaft 130. The latter is journaled lengthwise in bearings 131 arranged on the underside of the stave carrier, as shown in Figs. 1, 3, 4 and 18. The weight of the evener arms and jaws normally holds the same in their outermost position and their outward movement is limited by means of a stop device which preferably consists of a collar 132 secured to the central part of the evener rock shaft and provided with a stop finger 133 adapted to engage with the inner side of the adjacent bearing 131, as shown in Figs. 1 and 18. The weight of these evener arms and jaws is preferably counter-balanced for easing the work of the operator by means of a weight 134 which is secured to a rod 135 depending from the lower side of the stop collar 132, as shown in Figs. 1, 3, 4 and 18. This weight is preferably secured eccentrically to this supporting rod by means of a set screw 136, so that by turning this weight on this rod the effect of the same may be adjusted to secure the desired counter-balancing of the evener. In order to enable the operator to conveniently shift the evener arms and jaws with either one or both of his hands the jaws are provided with laterally projecting handles 137 which are arranged adjacent to the upper surface of the stave carrier. By this means the operator can shift the evener and at the same time hold the stave blank upon the stave carrier, thereby preventing the stave blank from being displaced while the same is being fed inwardly over the stave carrier against the side gage and underneath the saw. Inasmuch as both evener jaws are mounted on the rock shaft 130 the same are compelled to move transversely in unison, thereby insuring moving the stave blank in parallelism across the stave carrier and insure proper presentation of its inner longitudinal edge to the band saw for trimming it even and uniformly. The central and end portions of the evener rock shaft are preferably made square and the hub of the stop finger is provided with a

- correspondingly shaped opening to receive the central square part of the shaft and the hubs of the evener rock arms are likewise provided with correspondingly shaped openings which receive the end portions of this shaft, thereby compelling these parts to turn with the evener shaft but permitting the same to be adjusted lengthwise thereon into different positions as best suits the particular stave, which is being operated upon and also to suit the convenience of the operator. After adjustment these parts are retained in their proper position on the evener rock shaft by means of set screws 138, 139, as shown for instance in Figs. 1 and 18. While the stave blank is resting on the stave carrier and being moved upwardly against the teeth of the band saw the latter produces a pull upon the stave carrier which in the absence of any provision to prevent it might tend to displace the same. This, however, is prevented by a retaining device, which, as shown in Figs. 2, 8, 17 and 18 preferably comprises an anti-friction roller 140 mounted on the left hand carrier rock arm 100 and engaging with an abutment surface which is provided by a lug 141 secured to the upper side of the left hand supporting arm 53.
- In order to hold the stave blank in place, on the stave carrier after the same has been engaged and permit the operator to remove his hands from the stave blank after the initial part of the upward movement of the carrier has been effected a holding device is provided which preferably comprises one or more presser pins 142 which are adapted to engage with the upper side of the stave blank adjacent to the outer side of the saw before the stave blank is engaged by the same. Three of such presser pins are arranged vertically and in a longitudinal row lengthwise of the path of the saw. Each of these presser pins has its upper end guided in a vertical guideway 143 formed in one of the hangers 73, as best shown in Figs. 10 and 13 and is yieldingly held in its lowered position, so that its lower end is arranged below the teeth of the saw by means of a spring 144 arranged in the guideway and bearing at its lower end against the bottom of a socket 145 formed in the upper end of the presser pin while its upper end bears against the underside of the horizontal flange of the supporting angle bar. The downward movement of each presser pin is limited by a downwardly facing shoulder 146 formed on the exterior thereof and engaging with an upwardly facing shoulder 147 formed in the lower part of the guideway 143, as shown in Fig. 13. Upon lifting a stave blank by means of the stave carrier it is first engaged on its upper side by the presser pins which operate to hold the stave blank against the saw, as well as during the first part of its downward movement after the trimming operation has been completed. By this means the operator may remove his hands from the blank after the same has been engaged by the presser pins without liability of the blank becoming disarranged.
- In the operation of this machine one or both attendants stand adjacent to the outer sides of the operative stretches of the band saw and place the stave blanks successively upon the stave carriers. Thereafter each operator pushes the evener jaws inwardly so that the same engage with the outer longitudinal edge of the respective stave blank and move the same underneath the saw and into engagement with the side gage. The treadle is now depressed which causes the stave carrier to lift the stave blank and move its inner longitudinal portion across the path of the saw whereby the respective part of the stave blank is trimmed off on a curve suitable for forming a joint with others in making a bilge barrel. As soon as the saw engages the stave blank the operator may release the evener jaws so that they return to their outer inoperative position and after the cutting operation has been performed the treadle is released so that the stave carrier may drop into its lower inoperative position after which the operator reverses the stave for trimming its opposite longitudinal edge, this operation being repeated in like manner with each successive stave.
- This machine is very efficient in operation and permits of jointing barrel staves expeditiously and economically with comparative safety for the operator, with a minimum amount of wear on the working parts and a minimum expenditure of power. It has no delicate parts which are likely to get out of order, all of its working parts are arranged conveniently and are readily accessible for inspection, adjustment and repairs. Owing to the fact that the workmen stand outside of the machine while operating it the operation of the machine can be attended with greater freedom, safety and comfort to the operator.
- I claim as my invention:
1. A stave jointer comprising a pair of supporting wheels, a band saw mounted on said wheels and means for deflecting said saw between said wheels comprising a plurality of guide blocks arranged in a longitudinal row and engaging with the side of said saw, a flexible plate on which said blocks are mounted and means for flexing said plate.
  2. A stave jointer comprising a pair of supporting wheels, a band saw mounted on said wheels, and means for deflecting said saw between said wheels comprising a plurality of bearing blocks engaging with the

side of said saw, a flexible plate on which said blocks are mounted, means for flexing said plate, a supporting bar arranged adjacent to the saw, and a plurality of hangers 5 connecting said bar with said plate.

3. A stave jointer comprising a pair of supporting wheels, a band saw mounted on said wheels, and means for deflecting said saw between said wheels comprising a plurality of bearing blocks engaging with the side of said saw, a flexible plate on which said blocks are mounted, a supporting bar arranged adjacent to the saw, a plurality of hangers connected with said plate, and means for adjustably connecting said hangers with said bar.

4. A stave jointer comprising a pair of supporting wheels, a band saw mounted on said wheels, and means for deflecting said saw between said wheels comprising a plurality of bearing blocks engaging with the side of said saw, a flexible plate on which said blocks are mounted, a supporting bar arranged adjacent to the saw, a plurality of hangers connected with said plate, and means for adjustably connecting said hangers with said bar comprising a clamping screw connecting each of said hangers with said plate, a push screw mounted on said bar and engaging with said hanger, and a draw screw mounted on said bar and engaging with said hanger.

5. A stave jointer comprising a pair of supporting wheels, a band saw mounted on said wheels, and means for deflecting said saw between said wheels comprising a plurality of bearing blocks engaging with the side of said saw, a flexible plate on which said blocks are mounted, a supporting bar arranged adjacent to the saw, a plurality of hangers connected with said plate, and means for adjustably connecting said hangers with said bar comprising a clamping screw connecting each of said hangers with said plate, a push screw mounted on said bar and engaging with said hanger, and a draw screw mounted on said bar and engaging with said hanger, said push and draw screws being arranged at right angles 50 to said clamping screw.

6. A stave jointer comprising a band saw, a plurality of bearing blocks engaging with one side of said saw and operating to deflect the same, a plurality of individually 55 adjustable retaining blocks engaging with different parts of the opposite side of said saw, a supporting bar on which said blocks are mounted, a main frame, and means for detachably connecting said bar with said frame.

7. A stave jointer comprising a band saw, a plurality of bearing blocks engaging with one side of said saw and operating to de-

flect the same, a plurality of individually adjustable retaining blocks engaging with different parts of the opposite side of said saw, 65 a supporting bar on which said blocks are mounted, a main frame, and means for detachably connecting said bar with said frame comprising brackets mounted on the frame and provided with outwardly opening slots, and bolts arranged in said slots and connecting with said bar.

8. A stave jointer comprising a band saw, a plurality of bearing blocks engaging with 75 one side of said saw and operating to deflect the same, a plurality of retaining blocks engaging with the opposite side of said saw, a supporting bar on which said blocks are mounted, a main frame, and means for detachably connecting said bar with said frame comprising brackets mounted on the frame and provided with outwardly opening 80 slots, and bolts arranged in said slots and connecting with said bar, clamping blocks arranged on the inner side of said bar and projecting upwardly behind said brackets, a pivot bolt connecting each clamping block with said bar, and an adjusting screw arranged on each clamping block and 85 engaging with the rear side of said bracket.

9. A stave jointer comprising a band saw, a plurality of bearing blocks engaging with one side of said saw and operating to deflect the same, a plurality of individually 95 adjustable retaining blocks engaging with different parts of the opposite side of said saw, a supporting bar on which said blocks are mounted, a main frame, and means for detachably connecting said bar with said frame comprising brackets mounted on the frame and provided with outwardly opening slots, and bolts arranged in said slots and connecting with said bar, clamping blocks arranged on the inner side of 100 said bar and projecting upwardly behind said brackets, a pivot bolt connecting each clamping block with said bar, an adjusting screw arranged on each clamping block and 105 engaging with the rear side of said bracket and a yielding detent device for holding said clamping block in position relatively to said bar and bracket.

10. A stave jointer comprising a band saw, a plurality of bearing blocks engaging 115 with one side of said saw and operating to deflect the same, a plurality of retaining blocks engaging with the opposite side of said saw, a supporting bar on which said blocks are mounted, a main frame, and 120 means for detachably connecting said bar with said frame comprising brackets mounted on the frame and provided with outwardly opening slots, and bolts arranged in said slots and connecting with said bar, 125 clamping blocks arranged on the inner side

of said bar and projecting upwardly behind said brackets, a pivot bolt connecting each clamping block with said bar, an adjusting screw arranged on each clamping block and 5 engaging with the rear side of said bracket, and a yielding detent device for holding said clamping block in position relatively to

said bar and bracket comprising a detent pin arranged in a guideway in said clamping block and engaging with the inner side of 10 said bar, and a spring arranged in said guideway and bearing against the rear end of said pin.

EDWIN F. BEUGLER.
